SELF-CLEANING FORGING DIE

Floyd E. Davis, Gary, Ind., assignor to United States Steel Corporation, a corporation of New Jersey

Application July 31, 1952, Serial No. 301,917

2 Claims. (Cl. 78—80)

1

The present invention relates generally to metal forging and more particularly to a self-cleaning die especially suitable for forging railroad car wheels.

In the manufacture of railroad car wheels, the heated wheel blank is removed from the heating furnace and descaled before the initial forging operation. The initial descaling of the wheel blank is very important in the manufacture of quality railroad car wheels. If the descaling is not thorough, particles of scale remaining on the blank will fall off into the die cavity during the subsequent forging operation and imbed themselves into the surface of the forged wheel. The presence of these surface defects most generally necessitates the rejection of the railroad wheel after the surface has been machined and pits discovered.

Several types of apparatuses and methods have been devised in an attempt to insure thorough descaling before forging. However, none of these have been entirely successful. With the best practice devised up to the time of my invention, some particles of scale continued to fall off to the wheel blank as it was being pressed in the forging die.

Most widely used of the present day descaling machines is the chain type descaler. This machine cleans the ends of the wheel blank satisfactorily but does not adequately descale the periphery of the blank, whether it is round or rectangular, since minute particles of scale adhere to the peripheral surfaces of the blank after the descaling operation has been completed.

Heretofore, after the ends of the wheel blank had been cleaned by the chain type descaling machine, the blank was placed, on end, in the forging die and moved into the forging press where the flattening and initial forming operation was performed. As the blank was being flattened, the scale broke loose from its periphery and fell into the forging die cavity where it remained to be pressed into the forged wheel and cause surface defects which resulted in rejection of the wheel. Rejection was usually necessary since the cavities or pits left in the surface of the wheel by the removal of the hard and brittle pressed-in scale were usually too large to be removed by machining.

The mechanical operation performed by the forging press in flattening the wheel blank is the most efficient method for removing the scale from the periphery of the blank. At forging temperature the steel wheel blank is in a plastic condition while the scale is inelastic, hard and brittle.

2

Therefore as the steel flows and deforms under the forging pressure, cleavage occurs at the surface between the steel and the scale which causes the scale to break and spall off into the die. This accumulation of scale in the die would be pressed into the surface of the steel as that flowing metal fills the die and causes surface defects and subsequent rejections as explained above.

I propose to solve this problem by providing a self-cleaning wheel-forging die which will clean itself of the particles of scale which fall from the surface of the wheel block as the wheel is being forged.

Accordingly, it is an object of my invention to provide a forging die having means incorporated therein wherein pressure fluid may be introduced to remove fallen scale from the forming cavity of the die as a workpiece is being forged therein.

This and other objects will become apparent after referring to the following specification and attached drawings, in which:

Figure 1 is a plan view;

Figure 2 is a cross-sectional view; and

Figure 3 is a cross-sectional view of a modification.

Referring more particularly to the drawings, reference numeral 2 indicates the main body portion of a lower wheel-forming die which is used in conjunction with an upper die 4 to forge a wheel blank from a blank workpiece W which may be either rectangular or cylindrical. The main body 2 is provided with an axial center bore 6 in which is slidably fitted a stripper pin 8. The diameter of the center bore 6 is slightly greater than the diameter of the pin 8 so as to allow water and fine particles of scale to fall through the bore and not block the action of the stripper pin. The upper end of the main body 2, as shown in Figures 1 and 2, is provided with an annular recess 10 having a concentric cut-out portion 12 in its bottom surrounding the axial bore 6. The cut-out portion 12 forms an annular shoulder 14 spaced from the axial bore 6. An annular ring member 16 is removably disposed in the bottom of the recess 10 spaced from and surrounding the bore 6. The annular ring 16 is provided with an angular upper surface which is adapted to support the workpiece W, as shown in Figure 2, and a cut-away bottom surface which rests partly on the cut-out portion 12 of the recess 10 and partly on the annular shoulder 14. The outer periphery of the ring 16 terminates on the shoulder 14 short of the recess wall 18 to form an annular space 20 between the ring and the

wall. When the upper die 4 presses the workpiece W into the recess 10, the ring 16, together with the grooves and shoulders of the recess 10 forms the hub, web and rim of the wheel.

The forging die structure thus far described is conventional with the exception of the pressure fluid system of my invention which will now be described in detail.

An annular groove 22 is provided in the main body 2 in the bottom of the recess 10 beneath the annular ring 16. A plurality of radial grooves 24 are spaced continuously along the shoulder 14 under the ring 16. The radial grooves 24 communicate with the annular groove 22 and extend therefrom to the annular space 20 which is formed between the outer periphery of the ring 16 and the wall 18 of the recess. An axially directed fluid duct 26 within the body 2 may be connected with the annular groove 22 at two diametrically opposed points as shown in Figures 1 and 2. Each of the ducts 26 is connected with a radially disposed pressure fluid supply duct 28 which extends to the outer periphery of the body 2. The outer end of each of the fluid supply ducts 28 may be provided with a pipe tap 30 whereby it may be connected to a fluid supply pipe.

In operation, fluid pressure is first admitted into the fluid supply ducts 28 in sufficient quantities to insure discharge of the fluid from the grooves 24 into the space 20. Although any suitable pressure fluid may be used, I have found it convenient and preferable to use compressed air. After the air pressure has been turned on, the wheel blank W is placed in the recess of the die in the customary manner and upper die 4 is actuated to initiate the forging of the wheel. As the upper die 4 presses down on the workpiece W, it tends to deform it and scale is broken loose from its surface. As the particles of scale fall, the air stream issuing from the radial grooves 24 picks up the particles and blows them from the die recess. The continuous air blast insures that no falling scale will remain in the cavity 20 of the die block 2 to be pressed into the surface of the wheel as it is formed.

The wheel is removed from the die after it is formed and immediately thereafter the die is filled with water which is immediately blown out by the air blast and the die is ready to receive another blank.

Although I have found it preferable to provide two ducts 28 and 26, it will be understood that this number may be varied from one to a greater number if desired. Also, it will be noted that the air supply duct 28 may be connected directly with the annular groove 22 if desired.

I have found it necessary to provide additional air outlets in addition to the radial grooves 24 in the case of dies used for forging the larger size railroad car wheels. Where such larger size wheels are being formed, I have found it expedient to include a series of spaced vertical pas-

sages 32 extending from the groove 22 through the annular ring 16. These vertical air passages are of little use in the forging of small size wheels since they become covered by the spreading metal of the workpiece in a short time after forging is commenced. However, in the case of larger wheels, they are effective in disposing of the great amount of scale which falls from the periphery of the larger workpiece as it is being pressed.

While one embodiment of my invention has been shown and described, it will be apparent that other adaptations and modifications may be made without departing from the scope of the following claims.

I claim:

1. A forging die for forming a wheel having a hub, web and rim from a blank workpiece which comprises a main body portion having an axial bore therethrough and an annular recess in one end thereof, a stripper pin slidably fitted in said bore, the diameter of said bore being slightly larger than the diameter of said pin, the bottom of said recess being provided with a concentric cut-out portion surrounding said axial bore to form an annular shoulder spaced from the bore, an annular ring removably disposed in the cut-out portion of said recess spaced from said axial bore, said ring having an angularly shaped upper surface adapted to support said blank workpiece and a cut-away bottom surface adapted to rest partly on the bottom of said cut-out portion and partly on said annular shoulder, the outer periphery of said ring terminating short of the wall of said recess to form an annular space between the ring and the wall, said ring being adapted to cooperate with said recess to form the hub, web and rim of a wheel when a blank workpiece is pressed in said recess, said main body having an annular groove adjacent the bottom of said recess beneath said annular ring, and a plurality of spaced radial grooves extending from said annular groove to said space between said ring and the wall of the recess, said main body having at least one pressure fluid duct connected with said annular groove at one end and with a source of pressure fluid at its other end for supplying pressure fluid to said annular space through said annular groove and said radial grooves.

2. A forging die as defined in claim 1, characterized by a plurality of spaced pressure fluid passages extending axially through said ring from said annular groove.
